UNITED STATES PATENT OFFICE

2,078,834

RADIO SCRIP CONTROL DEVICE

Edward Joseph Brennan, Springfield, Ill.

Application November 7, 1934, Serial No. 751,962
Renewed December 24, 1936

4 Claims. (Cl. 40—31)

This invention relates to a radio scrip control device. One of the objects of the invention is to provide for regulating and timing features, programs, or any announcements where scrip is used and has particular application to radio broadcasts, public speaking and other auditions.

Another feature of the invention is the provision of electrically propelled and adjustable speed regulator features that move the web of scrip in conjunction with the time allotted for speeches, programs and announcements thereby eliminating all worry of running over or under the time allotted for the rendition.

Another feature of the invention is the provision of the scrip being formed all in one piece on a web that passes within the view of the person announcing thereby overcoming the possibility of repeating or confusion because there will be an indicator upon which the vision is concentrated.

Further objects of the invention are to provide in a device of the character referred to that is small and compact, and which may be supported on a table, speaking stand, or microphone, that is thoroughly reliable for its intended purpose, comparatively inexpensive to manufacture, and requiring the minimum of repair expense.

With the foregoing and other objects in view, the invention consists of a novel combination and arrangement and construction of parts as will be hereinafter more specifically described and illustrated in the accompanying drawings, wherein is shown the preferred embodiment of the invention, but it is to be understood that changes, variations and modifications may be resorted to without departing from the spirit of the claims hereunto appended.

In the drawings wherein like reference characters indicate corresponding parts throughout the several views:

Figure 1 is a vertical detailed section through the device of the present invention taken substantially on the line 1—1 of Figure 2 and looking in the direction of the arrows.

Figure 2 is a detailed section taken substantially on the line 2—2 of Figure 1 and looking in the direction of the arrows.

Figure 3 is a central vertical section through the casing showing the mechanism in side elevation.

Figure 4 is a fragmentary top plan view of the device in accordance with the present invention.

Figure 5 is a vertical section through the driving spool drum and shaft.

Figure 6 is a fragmentary perspective view of a corner of the partition wall.

Figure 7 is a fragmentary portion of a side wall of the casing showing the control member for regulating the speed of the driving motor.

Referring to the drawings in detail, A indicates a metal casing formed of a bottom wall 10 and integral end walls 11, 12 rising therefrom. The one end wall 11 is perpendicular to the bottom, while the other end wall 12 is curved as is clearly shown in Figure 3 of the drawings.

The end walls 11 and 12 merge with the top wall 13 which is positioned diagonally with respect to the horizontal bottom wall 10. One side wall 14 is perpendicular to the bottom wall 10 and is formed integral therewith. The other side of casing A is open, and this open side is closed by the removable cover or side wall 15 formed with inturned flanges 16 about its perimeter that frictionally engages with the adjacent margins of the top, bottom, and end walls. The cover or removable side wall 15 is taken out to remove or apply the spools of script as will hereafter appear. It will be understood that it is preferred to make the end, bottom, top and one side wall integral.

In the center of the top wall 13 of casing A is a substantially rectangular opening 17 about the margin of which is a right angled flange 18 secured to the top wall. A rectangular magnifying glass 19 is held by the flange against the top wall about the opening 17. Magnifying glass 19 is divided transversely of the casing by the two lines 20, 21, made in the glass, which lines demarcate a central panel P that attracts the attention of the announcer that his place on the script lies under this panel. It will be seen that the panel P prevents the announcer from losing his place or otherwise becoming confused during the audition.

Adjacent one end of the magnifying glass 19 is mounted a segmental shaped light reflector 22 in which is confined the electric light bulb and socket 23. The rear wall 24 of the reflector is arcuate. The reflector 22 throws the light downwardly through the magnifying glass panel so that the script passing under the opening 17 may be easily read.

There is a substantially rectangular partition plate or wall 25 mounted longitudinally of the casing A in a vertical position. One edge is secured to the bottom wall and the adjacent edge is secured to end wall 11, preferably by welding the edges to the inner faces of the walls. The vertical partition plate 25 is formed with a pocket

26 on the middle of the free edge 27 and the ends of this pocket are defined by the integral sleeves 28. A bearing wing 29 projects above the longitudinal free edge 27 and on the lower end of this wing are a pair of sleeves 30 which extend into the pocket 26. Sleeves 28 and 30 register with each other at each end of the pocket and there is a rod 31 extending across the pocket having each end rotatable in the registering sleeve 10 thereby forming a hinge. A coil spring 32 is circumposed on the rod in pocket 26 and has one end 33 bearing on the wing 29 and the other end bearing on the face of partition plate 25. Along the other vertical edge 35 of partition plate 25 15 is hinged another bearing wing 36 mounted to swing on the vertical pin 31', which mounting is similar in all respects to the mounting for the bearing plate 29. Thus it will be seen that the bearing wings 29 and 36 are urged inwardly (referring to Figure 1 of the drawings) under the tension of the coil spring 32. Bearing wing 29 swings on a horizontal axis whereas bearing wing 36 swings on a vertical axis.

A driving web carrying spool is indicated generally at 37 and the web feeding spool is indicated generally at 38. Intermediate the ends driving spool 37 has the drum portion 39 thereof carried by drive shaft 40 which is rectangular in cross section so as to provide proper traction 30 for drawing the web 41 from the feed spool 38. The ends of this shaft 40 merge with pintles 42 one of which is journaled in side wall 14, and the other is journaled in the wing 36. A relatively large driving gear 43 is keyed to the pintles 35 42 for driving the driving spool 37.

Adjacent one end of opening 17 there is an idle roller 44 having one end journaled in wing 36 and the other end in side wall 14. Another roller 45 is mounted adjacent the other end of 40 opening 17 with one end journaled in wing 29 and the other end journaled in side wall 14. It will thus be seen that the web 41 is stretched across the inner face of the casing under the opening 17 by these rollers 44 and 45 while the 45 web is moving from the driving roller 37 being fed from the feed roller 38. There are two idling gear shafts 46, 47 between the feed and drive roller, each one being journaled at one end in the vertical partition plate 25 and at their other 50 ends in the side wall 14. These shafts 46, 47 carry the intermeshing gear train 48, 49 respectively which drives gear 43 on the driving web spool 37. A motor 50 is carried by the side wall 11 on a bracket 51 secured to the side wall by the 55 bolts 52. The motor 50 is an electric motor and on the shaft 53 thereof is a pinion gear 54 which meshes with the gear 49 whereby motion is transferred from the motor 50 to the driving web spool 37.

60 The feed spool 38 is free to move in its bearings. For this purpose a pintle 55 is journaled in the side wall 14 and another pintle 56 is journaled in the wing 29.

On the outside of the casing and on the outer 65 face of side wall 14 is a rotatable knob 57 carrying the pointer 58. The knob is on a shaft which extends into a conventional rheostat 59 which is connected by the electrical conductor wires 60 to the motor 50. The face of side wall 70 14 adjacent the knob 57 is formed with the circular dial 61 which has twelve radial divisions as clearly shown in Figure 7. Each division represents 5 minutes. The supply current of course is connected with the rheostat in the conventional manner and control knob 57 turning the rheostat 75

shaft will regulate the speed of electric motor 50.

By having the wings 29 and 36 hinged, feed spool 38 may be replaced at any desired time and so may the driven spool 37. It is the intention to have the script printed on the web 41 and wrapped on the feed spool 38. Script web 41 then passes over the respective rollers 44, 45 under the opening 17 and is wrapped up on the drive spool 37. As the script web 41 passes under the opening it is magnified and the announcer reads the script as it passes the center panel P.

The control dial or knob 57 regulates the speed of the motor on the same principle that the speed is regulated on an electric fan or any electric motor, control dial 57 being connected to a 15 shaft that goes through the side wall 14 to a resistance coil 59. The motor and resistance are so timed that by setting the pointer 58 on the dial to the numeral 3 a specified length of web script will pass between the spools in fifteen minutes, or when the dial is set to 6 a specified length of web script will pass in thirty minutes. The nearer the pointer is set to the numeral 12 on the dial the more power is cut out by the resistance slowing down the motor to any desired speed for the time allotted for the program; for instance, if thirty minute programs are printed on a six foot length of web 41, then by setting pointer on the dial at figure 6 the motor is so timed that it will run at the proper speed to end 30 the program in exactly thirty minutes.

Having described my invention, what is claimed as new is:

1. A radio script control device comprising a 35 casing including top, bottom and side walls, one of the latter of which is open, said top wall formed with a sight opening, a removable cover over the open side wall, a partition wall secured to the bottom wall adjacent the open side, a pair of yielding wings secured to the partition wall, 40 a web feeding spool and a driving web spool journaled at one end in a fixed side wall and at the other end journaled in the yielding wings one in each wing, a web connected with the feed and drive spools and extending therebetween so 45 that the indicia on the web may be viewed from the top of the casing, a motor inside the casing, and a driving connection between the motor and the driving web roll.

2. A radio script control device comprising a 50 casing including a top, bottom and side walls, one of the latter of which is open, said top wall formed with a sight opening, a removable cover over the open side wall, a partition wall secured to the bottom wall adjacent the open side, a pair 55 of yielding wings secured to the partition wall, a web feeding spool and a driving web spool journaled at one end in a fixed side wall and at the other end journaled in the yielding wings one in each wing, a web connected with the feed and 60 drive spools and extending therebetween so that the indicia on the web may be viewed from the top of the casing, a variable speed electric motor inside the casing, means mounted on the casing to regulate the speed of the motor, and a driving 65 connection between the motor and the driving web roll.

3. A radio script control device comprising a 70 casing including a top, bottom and side walls, one of the latter of which is open, said top wall formed with a sight opening, a removable cover over the open side wall, a partition wall secured to the bottom wall adjacent the open side, a pair of yielding wings secured to the partition wall, a 75 web feeding spool and a driving web spool jour-

nailed at one end in a fixed side wall and at the other end journaled in the yielding wings one in each wing, a web connected with the feed and drive spools and extending therebetween so that the indicia on the web may be viewed from the top of the casing, a variable speed electric motor inside the casing, means mounted on the casing to regulate the speed of the motor, a driving connection between the motor and the driving web 10 roll, and a magnifying member mounted on the casing in the area of the sight opening.

4. A radio scrip control device comprising a casing including a top, bottom and side walls, one of the latter of which is open, said top wall 15 formed with a sight opening, a removable cover over the open side wall, a partition wall secured to the bottom wall adjacent the open side, a pair

of yielding wings secured to the partition wall, a web feeding spool and a driving web spool journaled at one end in a fixed side wall and at the other end journaled in the yielding wings one in each wing, a web connected with the feed and drive spools and extending therebetween so that the indicia on the web may be viewed from the top of the casing, a variable speed electric motor inside the casing, means mounted on the casing to regulate the speed of the motor, a driving connection between the motor and the driving web roll, a magnifying member mounted on the casing in the area of the sight opening, and a source of illumination carried by the outside of the casing equipped with a reflector to direct light on the sight opening. 15

EDWARD JOSEPH BRENNAN.
